CLAIM

The ornamental design for a collapsible camping table, as shown and described.

DESCRIPTION

FIG. 1 is a front, top, left-side perspective view of my design for a collapsible camping table according to the present specification;

FIG. 2 is a rear, bottom, right-side perspective view of FIG. 1;

FIG. 3 is a left-side elevational view of FIG. 1;

FIG. 4 is a right-side elevational view of FIG. 1;

FIG. 5 is a rear elevational view of FIG. 1;

FIG. 6 is a front elevational view of FIG. 1;

FIG. 7 is a top plan view of FIG. 1; and,

FIG. 8 is a bottom plan view of FIG. 1.

The dash type broken lines shown in the drawings represent portions of the collapsible camping table that form no part of the claimed design.

The relatively light and thin shade lines shown in the drawings are included for the purpose of indicating surface contour and not surface decoration.
